TRIGGER MECHANISM FOR FIREARMS

Clyde B. Ferrel, San Francisco, Calif.

Application December 15, 1939, Serial No. 309,363

11 Claims. (Cl. 42—69)

This invention relates to a trigger mechanism for firearms such as rifles, machine guns and the like, and especially to a trigger mechanism embodying two triggers which are operable independently of each other to effect firing control.

The object of the present invention is generally to improve and simplify the construction and operation of trigger mechanisms of the character described; to provide a trigger mechanism which embodies two triggers operable independently of each other, one trigger being a fire control trigger and the other functioning as an automatic or machine gun trigger; to provide a fire control trigger which permits smooth, easy action and which is operable to release the firing plunger both during pull or release of the trigger; and further, to provide a trigger mechanism which is simple in construction and operation, requires few parts, eliminates fine adjustments, and permits sturdy construction.

The trigger mechanism is shown by way of illustration in the accompanying drawings, in which:

Fig. 1 is a longitudinal section of a gun showing a portion of the bolt action and the trigger mechanism;

Fig. 2 is a side elevation on the trigger mechanism partially broken away;

Fig. 3 is a cross section taken on line III—III of Fig. 1;

Fig. 4 is a perspective view of the firing plunger head;

Fig. 5 is an enlarged vertical longitudinal sectional view of the trigger mechanism and a portion of the firing plunger and head;

Fig. 6 is a perspective view of the trigger frame;

Fig. 7 is a perspective view of the triple latch arm;

Fig. 8 is a perspective view of a fire control trigger;

Fig. 9 is a perspective view of a machine gun trigger; and

Fig. 10 is a horizontal section taken on line X—X of Fig. 1;

Fig. 11 is similar in view to Fig. 5, drawn on a smaller scale, showing the shoulder 15d of the firing head in engagement with the latch arm 15.

Referring to the drawings in detail and particularly to Figs. 5 and 6, A indicates in general a trigger frame at the front and lower end of which is formed a trigger guard 2, and at the rear end of which is formed a web 3 to which the stock of the gun is secured, as shown at 4 in Fig. 1. Formed at the upper and rear end 55

of the trigger frame is a ring-shaped member 5 and a forwardly extending clamping plate 6, whereby the main frame B of the gun (see Fig. 1) is partially secured. On the upper surface of the frame are formed stepped faces 7 and 8, and intermediate the stepped faces is a cut-away or cored-out portion 9 which extends down through the web 3 to the bottom of the guard 2. This cored-out portion also extends into the face 7, and semi-circular flanges 10 form the side walls thereof. The cored-out portion 9 is provided for the reception of two independently actuated triggers C and D which will hereinafter be referred to as the fire control trigger and the automatic or machine gun trigger, respectively (see Figs. 8 and 9). Secured to the upper surface of the face 7 by a screw 11 is a triple latch member, generally indicated at E (see Fig. 7). This is made of spring steel and is divided longitudinally into three arms, 14—14 and 15. Each of these arms terminates in shoulders which will function as latches, as will hereinafter be described.

Below the latch shoulders formed on the arms 14 are bearing bosses 14a—14a which are centrally drilled to receive and support a bearing pin 16. Similarly formed on the end of the central arm 15 is a boss 15a which is vertically slotted as indicated at 15b to permit the bearing pin 16 to extend therethrough and to move vertically therein, and formed on the rear side of the boss 15a is a lug 15b, the function of which will later be described.

The main function of the triple latch member B is to control the firing plunger 17, which is hereinafter referred to, and to form a support for the fire control trigger C. The upper end of this trigger is forked and consists of a pair of spaced bearing lugs 18—18 which are centrally drilled to receive and to be hung from the bearing pin 16. The lugs are connected by a cross-piece 19 (see Fig. 8) and formed integrally therewith is the finger piece of the trigger C. Also carried by the crosspiece is the pin 20, and forming extensions of the lugs 18—18 are cheeks 18a which serve to guide the trigger against lateral movement within the trigger frame, and which also function as a trigger stop, as will hereinafter appear.

Before describing the operation of the trigger mechanism, a brief description of the bolt action, the firing pin and firing plunger must be submitted, as the trigger mechanism controls the operation of these parts. When the shell, cartridge, or other form of ammunition employed is detonated by the firing pin 30, energy is applied to the

bolt head 31 to force it rearwardly a predetermined distance. During this predetermined movement, the bolt head is released, permitting the energy to react on the bolt sleeve 32 and to drive it rearwardly against the tension of the spring 33. A secondary sleeve 34 moves rearwardly in unison with the bolt sleeve and serves several functions, among which will be mentioned the following:

First, a head member 35 carried by the intermediate sleeve 34 engages the plunger head 36 of the firing plunger 17 and thereby functions to reset or cock it. Secondly, during the return movement of the members 31, 32, 34 and 35, the firing plunger spring 38 is recompressed.

Suffice it to say that the firing plunger head 36 is controlled by the trigger C, or in other words is released when the trigger C is pulled. When released, the firing plunger is shot forward by the action of the spring 38 and thereby strikes the head 30a of the firing pin, causing it to strike and detonate the cartridge or other form of ammunition employed. A portion of the energy produced by the detonation of the cartridge is utilized to propel the members 31, 32, 34 and 35 rearwardly a sufficient distance to reset or cock the plunger firing head 36, and thereafter to place the spring 38 under compression, and the plunger firing head will not be released again until the trigger C is pulled.

In order that the firing plunger head may cooperate with the triple latch arm E, reference will be made to Fig. 4 of the drawings, as it will there be seen that the under surface of the head 36 is provided with a pair of shoulders 14d, which cooperate with the latch arms 14-14, and that a third and forwardly positioned shoulder 15d is provided which cooperates with the latch arm 15. Also it will be noted that a concave or rounded depressed surface 40 is formed rearwardly of shoulders just referred to. With this construction in mind, the operation of the trigger C will be as follows:

Referring to Fig. 5, it will be noted that the latch arms 14-14 are raised, and that they engage the shoulders 14d of the plunger firing head 36, thereby retaining or holding it together with the plunger 17 in a cocked position. If the gun is to be fired, a pull will be exerted on the trigger C in the direction of arrow a, and when this takes place, pin 20 will engage lug 15b formed in the rear end of arm 15, and as the end of this arm engages the under surface of the head 36, arm 15 will remain stationary. Hence pin 20 will function as a fulcrum point about which the trigger swings while it is being pulled from the full line to the dotted line position. The bearing pin 16, as previously stated, extends through the lugs 18 of the trigger, and as the trigger swings about the fulcrum point or the pin 20, pin 16 will swing or will be pulled downwardly from the full line to the dotted line position shown in Fig. 5, and as the pin also extends through the bearing bosses 14a of the latch arms 14-14 they will also be pulled downwardly away from the shoulders 14d, and the firing head 36 will thus be released. When released it will, together with the plunger 17, be propelled forwardly by the spring 38, and, as such, will strike the head 30a of the firing pin 30, causing this to strike the cartridge or other form of ammunition employed, thereby causing detonation. The moment detonation takes place, energy becomes available and, as previously stated, this causes rearward movement of the parts 31, 32, 34 and

35, causing the member 35 to force the head 36 and the plunger 17 rearwardly again past the triple latch arm.

At this point the spring 33 reaches its full compression and returns the other members to their normal position, while the firing head 36 on the plunger 17 will be stopped and retained in cocked position by the triple latch arm. That is, it should be remembered that the arms 14-14 and 15 are made of spring steel and when arms 14 are pulled downwardly into the same plane as the arm 15 by means of the trigger C, there is a tendency for all of the arms together with the trigger to spring upwardly the moment the head 36 is released. Thus on the return movement of the head 36 the several latch arms are in the raised position and are momentarily depressed by the head 36 during its return movement. But they will again immediately raise when the head 36 passes to a point rearwardly of the same. Hence when it starts its forward movement again, shoulder 15d will engage the central latch arm 15 as shown in Fig. 11. Then by releasing the pull on the trigger, arms 14 will be released and swing upwardly, while arm 15 will be depressed, thus pulling it out of engagement with the shoulder 15d and permitting the arms 14 to engage the shoulders 14d. The gun is thus re-cocked and ready for firing.

The description thus far submitted in connection with the trigger C describes the rearward pulling action thereon. Another method of utilizing the trigger C will be described as follows:

If the gun is to be fired, the operator pulls on the trigger C but he gives it a quick jerk or pull. In doing so, he releases or pulls the latch arms 14 downwardly as previously described, but at the same time there is a tendency to pull the trigger beyond the releasing position. In doing so, the cheeks 18a forming a part of the lugs 18 on the trigger will engage stop shoulders 15c formed on opposite sides of the semi-circular guide flanges 10 (see Figs. 5 and 6) and when these stop shoulders are engaged, the cheeks 18a become a fulcrum point which tends to lift all three latch arms upwardly. When such upward movement takes place, that is, when a quick jerk is imparted to the trigger, a rounded nose 41 on the rear end of the latch arm 15 moves upwardly into the concave or recessed portion 40 formed on the under side of the firing head, and thus retains the firing head against release. Then by slowly releasing the pull on the trigger C so as to permit it to swing forwardly, the firing head will be released and the cycle of operation previously described in connection with the firing plunger, firing pin, and other parts will be repeated.

Thus it will be seen that the trigger C may release the firing head 36 by rearward pull and also during release of forward movement of the trigger. The last described action of the trigger is the preferred one, as this provides an exceedingly smooth and easy action in connection with the release of the firing head, which eliminates any tendency to flinch or jerk the gun when firing.

The trigger action here shown may also be utilized for rapid fire or machine gun action, the trigger D being employed for this purpose. If rapid fire is desired, the operator merely moves his finger from the trigger C to engage the lower extension 25 of the trigger D. By exerting pressure and pulling this trigger rearwardly, it will obviously swing about the fulcrum point of

pin 23. In doing so, the fingers 24 will engage the bearing bosses 14a of the latch arms 14, and these will be depressed and will, together with the latch arm 15, be held in depressed position as long as the trigger D is held in its rearward position. Thus the firing head 36 is free to reciprocate without interference or retention by the latches, and automatic or machine gun firing is obtained.

The mechanism disclosed is exceedingly simple, few parts being employed, and the parts employed are sturdy in construction. The triple latch is secured by a single member, to wit, the screw 11, and it can not swing as the forward end is provided with an extension e which enters between a pair of lugs d—d formed at the rear end of the face 7 of the trigger frame. The extension e lies between the lugs d—d and thus secures the triple latch member against swinging movement. It is further retained against swinging or lateral movement by the bearing bosses 14a lying between the lugs 18—18 of the trigger C. The extension cheeks 18a of this trigger engage the exterior surfaces of the semi-circular lugs 10, shown in Fig. 6, and lateral movement of the trigger within the frame is also prevented.

The pivotal support for the trigger C is the bearing pin 16, but as this is supported in the bearing bosses 14a of the arms 14, it becomes a floating support for the trigger which permits it to yield both when the trigger C is operated and when engaged by the firing head 36.

Fine adjustments are entirely eliminated, as the movement of the triple latch arms is considerable, thereby permitting the use of shoulders 14d and 15d having liberal clearances.

It may otherwise be stated that the opposite side faces of the trigger frame shown in Fig. 6 are flanged, as shown at 45. These flanges form a support for the main gun frame B which is U-shaped at its lower side, as shown in Fig. 3, or in other words, provided with side flanges 46. This frame is partly secured by the ring-shaped member 5 and the lug 6, and it is also secured by the pins 23 and 23a extending through the gun frame and the trigger frame.

While certain features of my invention have been more or less specifically described and illustrated, I nevertheless wish it understood that changes may be resorted to within the scope of the appended claims.

Having thus described and illustrated my invention, what I claim and desire to secure by Letters Patent is:

1. In a trigger mechanism of the character described the combination with a spring actuated firing plunger of a latch engageable with the plunger to retain it in a cocked position, a second latch normally maintained out of engagement with the plunger, a pivotally mounted trigger, means actuated by the exerting of a quick pull on the trigger for disengaging the first latch and for engaging the second latch with the plunger, said second latch disengaging and releasing the plunger during return movement of the trigger, a second trigger, and means actuated by said trigger for maintaining both latches out of engagement with the plunger.

2. In a mechanism of the character described, a main gun frame, a trigger frame secured thereto, a spring actuated firing plunger reciprocally mounted in the main frame above the trigger frame, a pair of spring actuated laterally spaced latch arms secured to the trigger frame be-

low the plunger, a pair of spaced shoulders on the lower face of the plunger with which said latch arms normally engage to retain the plunger in a cocked position, a pivotally mounted trigger in the trigger frame, and means actuated by a pull on the trigger for simultaneously retracting both latch arms to release the plunger.

3. In a mechanism of the character described, a main gun frame, a trigger frame secured thereto, a spring actuated firing plunger reciprocally mounted in the main frame above the trigger frame, a pair of spring actuated laterally spaced latch arms secured to the trigger frame below the plunger, a pair of spaced shoulders on the lower face of the plunger with which said latch arms normally engage to retain the plunger in a cocked position, a third spring actuated latch arm disposed between the pair of latch arms, a concave surface formed in the plunger rearwardly of the shoulders, said third latch arm being normally maintained out of engagement with said concave surface, and a trigger pivotally mounted in the trigger frame, said trigger being selectively operable to actuate the several latch arms to release the firing plunger either during a pull on the trigger or during return movement of the trigger.

4. In a mechanism of the character described, a main gun frame, a trigger frame secured thereto, a spring actuated firing plunger reciprocally mounted in the main frame above the trigger frame, a pair of spring actuated laterally spaced latch arms secured to the trigger frame below the plunger, a pair of spaced shoulders on the lower face of the plunger with which said latch arms normally engage to retain the plunger in a cocked position, a third spring actuated latch arm disposed between the pair of latch arms, a concave surface formed in the plunger rearwardly of the shoulders, said third latch arm being normally maintained out of engagement with said concave surface, a bearing boss on each of the first named latch arms, a bearing pin supported by said bosses, and a trigger pivotally mounted on said pin, said trigger being selectively operable to actuate the several latch arms to release the firing plunger either during a pull on the trigger or during return movement of the trigger.

5. In a mechanism of the character described, a main gun frame, a trigger frame secured thereto, a spring actuated firing plunger reciprocally mounted in the main frame above the trigger frame, a pair of spring actuated laterally spaced latch arms secured to the trigger frame below the plunger, a pair of spaced shoulders on the lower face of the plunger with which said latch arms normally engage to retain the plunger in a cocked position, a third spring actuated latch arm disposed between the pair of latch arms, a concave surface formed in the plunger rearwardly of the shoulders, said third latch arm being normally maintained out of engagement with said concave surface, a bearing boss on each of the first named latch arms, a bearing pin supported by said bosses, a trigger pivotally mounted on said pin, a lug on the end of the third latch arm, and a pin on the trigger, said pin engaging the lug and forcing the third latch arm against the under surface of the plunger when a pull is exerted on the trigger to swing it about the bearing pin, said trigger simultaneously retracting the pair of latch arms to release the plunger.

6. In a mechanism of the character described, a main gun frame, a trigger frame secured there-

to, a spring actuated firing plunger reciprocally mounted in the main frame above the trigger frame, a pair of spring actuated laterally spaced latch arms secured to the trigger frame below the plunger, a pair of spaced shoulders on the lower face of the plunger with which said latch arms normally engage to retain the plunger in a cocked position, a third spring actuated latch arm disposed between the pair of latch arms, a concave surface formed in the plunger rearwardly of the shoulders, said third latch arm being normally maintained out of engagement with said concave surface, a bearing boss on each of the first named latch arms, a bearing pin supported by said bosses, a trigger pivotally mounted on said pin, a lug on the end of the third latch arm, and a pin on the trigger, said pin engaging the lug and forcing the third latch arm against the under surface of the plunger when a pull is exerted on the trigger to swing it about the bearing pin, said trigger simultaneously exerting a downward pull on the bearing pin and the pair of latch arms to release the plunger.

7. In a mechanism of the character described, a main gun frame, a trigger frame secured thereto, a spring actuated firing plunger reciprocally mounted in the main frame above the trigger frame, a pair of spring actuated laterally spaced latch arms secured to the trigger frame below the plunger, a pair of spaced shoulders on the lower face of the plunger with which said latch arms normally engage to retain the plunger in a cocked position, a third spring actuated latch arm disposed between the pair of latch arms, a concave surface formed in the plunger rearwardly of the shoulders, said third latch arm being normally maintained out of engagement with said concave surface, a bearing boss on each of the first named latch arms, a bearing pin supported by said bosses, a trigger pivotally mounted on said pin, a lug on the end of the third latch arm, a pin on the trigger, said pin engaging the lug and forcing the third latch arm against the under surface of the plunger when a pull is exerted on the trigger to swing it about the bearing pin, said trigger simultaneously exerting a downward pull on the bearing pin and the pair of latch arms to release the plunger, and a stop member with which the trigger engages when the pair of latch arms are released, said stop functioning as a fulcrum point and causing upward movement of the trigger and the third latch arm if a further pull is exerted, said upward movement of the third latch arm causing it to engage the concave surface of the plunger and to prevent release of the plunger, and said third latch arm releasing the plunger upon return movement of the trigger.

8. In a mechanism of the character described, a main gun frame, a trigger frame secured thereto, a spring actuated firing plunger reciprocally mounted in the main frame above the trigger frame, a pair of spring actuated laterally spaced latch arms secured to the trigger frame below the plunger, a pair of spaced shoulders on the lower face of the plunger with which said latch arms normally engage to retain the plunger in a cocked position, a third spring actuated latch arm dis-

posed between the pair of latch arms, a concave surface formed in the plunger rearwardly of the shoulders, said third latch arm being normally maintained out of engagement with said concave surface, a trigger pivotally mounted in the trigger frame, said trigger being selectively operable to actuate the several latch arms to release the firing plunger either during a pull on the trigger or during return movement of the trigger, a second trigger pivotally mounted in the trigger frame, and means actuated by said trigger for maintaining all of the latches out of engagement with the plunger.

9. In a mechanism of the character described, 15 a main gun frame, a trigger frame secured thereto, a spring actuated firing plunger reciprocally mounted in the main frame above the trigger frame, a pair of spring actuated laterally spaced latch arms secured to the trigger frame below the plunger, a pair of spaced shoulders on the lower face of the plunger with which said latch arms normally engage to retain the plunger in a cocked position, a third spring actuated latch arm disposed between the pair of latch arms, a concave 20 surface formed in the plunger rearwardly of the shoulders, said third latch arm being normally maintained out of engagement with said concave surface, a trigger pivotally mounted in the trigger frame, said trigger being selectively operable to 25 actuate the several latch arms to release the firing plunger either during a pull on the trigger or during return movement of the trigger, a second trigger pivotally mounted in the trigger frame, and a pair of fingers on said trigger engageable 30 with the bearing bosses of the first named pair of latches, said fingers causing depression of said latches and the bearing pin, and through the bearing pin, depression of the third latch, when a pull is exerted on the second trigger.

10. In a mechanism of the character described, 40 a main gun frame, a trigger frame secured thereto, a spring actuated firing plunger reciprocally mounted in the main frame above the trigger frame, a plurality of depressible spring actuated latches mounted in the path of travel of the plunger and normally engageable with the plunger to retain it in a cocked position, and a pair of triggers pivotally mounted in the trigger frame said triggers being independently operable to depress the latches to release the plunger.

11. In a mechanism of the character described, 45 a main gun frame, a trigger frame secured thereto, a spring actuated firing plunger reciprocally mounted in the main frame above the trigger frame, a plurality of depressible spring actuated latches mounted in the path of travel of the plunger and normally engageable with the plunger to retain it in a cocked position, and a pair of triggers pivotally mounted in the trigger frame, one trigger when pulled depressing the latches and releasing the plunger to fire ammunition, one shot for each pull of the trigger, and the other trigger maintaining the latches depressed to permit continuous operation of the plunger to fire ammunition as long as a pull is maintained on the trigger.

CLYDE B. FERREL.
